UNITED STATES PATENT OFFICE.

WILLIAM M. WETTER, OF WILLIAMSPORT, PENNSYLVANIA, ASSIGNOR OF ONE-HALF
TO LOUIS G. HULING, OF WILLIAMSPORT, PENNSYLVANIA.

RENEWABLE FUSE.

Application filed July 13, 1923. Serial No. 574,739.

To all whom it may concern:

Be it known that I, WILLIAM M. WETTER, a citizen of the United States, residing at Williamsport, in the county of Lycoming and State of Pennsylvania, have invented certain new and useful Improvements in Renewable Fuses; and I do declare the following to be a full, clear, and exact description of the invention, such as will enable others skilled in the art to which it appertains to make and use the same.

My invention relates to improvements in renewable fuses and more particularly to those of the type having an indicator which automatically comes into play when the fuse is blown, to indicate its condition without the necessity of inspecting its interior.

The principal object of the invention is to provide novel means for holding the indicator against detachment from the fuse body until the fuse wire or the like has blown, provision being made however whereby said indicator may then be quickly and easily removed so that a new fuse wire may be attached thereto for substitution in place of the blown fuse.

With the foregoing in view, the invention resides in the novel subject matter herein-after described and claimed, the description being supplemented by the accompanying drawings.

Figure 1 is a longitudinal sectional view of a fuse constructed in accordance with my invention.

Figure 2 is a duplicate of Figure 1 with the exception that it illustrates the condition of the fuse when the fuse wire has blown.

Figure 3 is a sectional view at right angles to Figures 1 and 2.

Figure 4 is a transverse section on line 4—4 of Figure 2.

Figure 5 is a perspective view of the indicator.

Figure 6 is a perspective view of the guide for the indicator.

In the drawings above briefly described, the numeral 1 designates a hollow body of insulation provided at one end with a removable cap or other closure 2 which preferably includes a centrally apertured disk 3 of insulation. The other end of the body 1 is surrounded by a threaded sleeve 4 adapted to be engaged with the shell of an ordinary fuse plug socket. Out of electrical engagement with the sleeve 4, the last men-

tioned end of the body 1 is provided with a central contact 5 for engagement with the usual contact of the socket, said contact 5 being here shown in the form of a binding screw. Adjacent this screw, the body 1 is formed with a guide eye 6 through which a renewable fuse wire 7 extends, the outer end of said wire being bound under the head of the screw 5, while the inner end of said wire is detachably connected with the inner end of an indicating rod 8 which passes slidably through the central aperture of the disk 3. The inner end of rod 8 is by preference provided with a head 9 and the fuse wire 7 is clamped against said head by a binding screw 10. When the fuse is thus held in place, the rod 8 is held in a retracted position, against the action of a coiled spring 11, one end of this spring being connected in any suitable manner with the rod while its other end re-acts against a guide bracket 12 which is mounted within the shell 1, being in electrical engagement with the sleeve 4 by means of a screw 13. Bracket 12 is formed with an opening 14 and with a reduced throat 15 leading from said opening through one end of said bracket, and the inner end of the indicating rod 8 is provided with a reduced neck 16 which may pass through the throat 15 when said rod is moved outwardly to the maximum and turned to aline the flat sides of the neck 16 with the sides of the throat 15. Ordinarily however when the fuse wire 7 is intact, the indicating rod 8 is held in the position shown in Figure 1 and the neck 16 is then below the throat 15 so that rod 8 cannot become disconnected from the bracket 12. As soon as the fuse wire blows, the spring 11 projects the indicating rod 8 beyond the cap 2 so that the condition of the device may readily be seen without examining its interior. Then, by removing the cap 2 and properly manipulating the rod 8, the neck 16 of the latter may be moved through the throat 15 of the guide bracket 12, thus permitting the entire rod to be removed from the body 1. The two ends of the old fuse wire are now disconnected by loosening the screws 5 and 10 and a new fuse wire may be secured against the head 9 while the rod 8 is removed from the body, permitting this operation to be performed with ease. Then, the rod and fuse are inserted bodily and the fuse is guided through the eye 6. When the rod 8 is again engaged

with the bracket 12 and forced inwardly to the desired extent against the tension of the spring 11, the free end of the fuse 7 is secured under the head of the screw 5, so that 5 said fuse prevents projection of the indicating rod 8 until it again blows. Fastening of the wire 7 by the screw 5 may of course be done either before or after re-applying the cap 2.

10 From the foregoing, taken in connection with the accompanying drawings, it will be seen that I have provided a very simple and inexpensive, yet highly efficient and desirable device for carrying out the object of the 15 invention. As excellent results have been obtained from the details disclosed, they are preferably followed, but within the scope of the invention as claimed, numerous minor changes may be made.

20 I claim:

1. A circuit cut-out comprising a body, a self-acting indicator carried by said body, a fuse connected detachably with said indicator at a point within the body and normally holding said indicator against operation, said fuse being also detachably connected with said body, and a detachable connection separate from the fuse connecting said indicator with said body and releasable 30 only when the fuse has blown.

2. A circuit cut-out comprising a body having spaced contacts, a removable self-

acting indicator having a portion in said body in electrical connection with one of said contacts, means for preventing removal of said indicator from said body until the former is manually moved in a manner other than its indicating movement, and a fuse preventing movement of said indicator in said manner until blown, said fuse being detachably connected with said indicator at a point within the body and being connected to the other of said contacts by a detachable connection accessible from the exterior of the body.

3. A circuit cut-out comprising a hollow body having spaced contacts and a removable closure, a guide secured in said body having an opening and a restricted throat leading thereto from the exterior of said guide, a spring-actuated rod passing slidably through said cover and guide and having a restricted neck permitting removal from said guide through said throat, and a fuse detachably connected to said rod at a point within said body, said fuse being anchored detachably to one of said contacts and normally holding said rod retracted with its neck spaced from said throat, said guide being in electrical engagement with the other of said contacts.

In testimony whereof I have hereunto affixed my signature.

WILLIAM M. WETTER.
